UNITED STATES PATENT OFFICE

170,508

BARBECUE OR SIMILAR ARTICLE

Jules Nisenson, Croton-on-Hudson, N. Y.

Application March 21, 1952, Serial No. 18,990

Term of patent 14 years

(Cl. D81—10)

To all whom it may concern:

Be it known that I, Jules Nisenson, a citizen of the United States of America, residing in Croton-on-Hudson, county of Westchester and State of New York, have invented a new, original, and ornamental Design for a Barbecue or Similar Article, of which the following is a specification, reference being had to the accompanying drawing, forming part hereof.

Figure 1 is a perspective view showing the front and one end of a barbecue or similar article embodying my new design; and Figure 2 is a perspective view showing the rear and other end thereof.

I claim:

The ornamental design for a barbecue or similar article as shown.

JULES NISENSON.
